ADVERTISING SIGN

Ray A. Bennett and Marion A. Sneed, Long Beach, Calif.

Application February 19, 1934, Serial No. 711,964

5 Claims. (Cl. 40—52)

This invention relates to an advertising sign wherein there is a plurality of compartments, each compartment being covered by a transparent or translucent sheet, and said compartments being successively illuminated by a novel timed contact arrangement.

An object of our invention is to provide an advertising sign comprising a plurality of compartments, each of which has a light therein, said lights being successively and continuously lit by a novel timed contact arrangement.

Another object is to provide an advertising sign of the character stated, in which a plurality of commutators separately controls the various lights in the sign, the contact brush on the various commutators being driven at different rates of speed whereby the various lights are lit in succession for varying lengths of time.

A further object is to provide an advertising sign of the character stated, in which pointers pass over the surface of the sign, said pointers extending to each sign in turn as it is illuminated.

Other objects, advantages and features of invention may appear from the accompanying drawings, the subjoined detailed description and the appended claims.

In the drawings:

Figure 1 is a plan view of our sign with the top transparent or translucent plates removed.

Figure 2 is a transverse, sectional view of the same.

Figure 3 is an enlarged, fragmentary side elevation of one form of commutator.

Figure 4 is a bottom plan view of the commutator shown in Figure 3.

Figure 5 is a top plan view of a modified form of commutator, the wiring arrangement being shown in connection therewith.

Figure 6 is a side elevation of the commutator shown in Figure 5.

Figure 7 is a plan view of a third type of commutator, the wiring arrangement being shown in connection therewith.

Figure 8 is a transverse, sectional view of the commutator shown in Figure 7.

Figure 9 is a wire diagram of the commutator arrangement shown in Figures 3 and 4.

Referring more particularly to the drawings, the numeral 1 indicates a sign housing in which we provide a plurality of radial partition walls 2 to form compartments 3.

A chronometer or motor 4 is mounted in the center of the housing 1 and drives three shafts 5, 6 and 7. These shafts are driven at different rates of speed, for example, one making a revo-

lution each twelve hours, another, each hour, and the third, each minute. Commutators 8, 9 and 10 are stationarily mounted around each of the shafts 5, 6 and 7, respectively. Each commutator is provided with a plurality of contact buttons 11, the number of buttons coinciding with the number of compartments 3.

The shafts 5, 6 and 7 are each provided with a spring contact finger 12 which rotates therewith and engages the contact buttons 11. As the shafts rotate, the spring fingers will successively contact the buttons 11 and will light an electric bulb 13 in each of the compartments 3.

The bulbs 13 are electrically connected to the contact buttons 11, as shown in Figure 9, and as the spring contact fingers 12 rotate, the bulbs will be successively lit for varying lengths of time.

Three pointers, 14, 15 and 16 extend over the compartments 3 and rotate at the same rate of speed as the shafts 5, 6 and 7, respectively. Thus, as each bulb is lit in a compartment, the pointer will extend over the top of the compartment, calling attention to the advertising sign displayed on a transparent or translucent cover.

In Figures 5 and 6, we have shown a commutator 17 which consists of a plurality of segments 18, in each of which there is provided a plurality of contacts 19 arranged in concentric rows.

Three contact arms 20, are separately mounted on co-axial shafts, and a spring finger 21 extends downwardly from each of the arms to engage the contacts 19 in succession. The wiring arrangement is substantially the same as previously described, in that the light bulbs 13 are lit in succession as the contact arms 20 sweep over the various contacts 19. There is one light bulb 13 for each segment 18.

In Figures 7 and 8, a commutator 22 is provided with three concentric rows of upstanding contact bars 23, 24 and 25. Three contact arms 26, 27 and 28 are each mounted on a separately driven shaft and the shafts are co-axially arranged. Each of the arms 26, 27 and 28 is provided with a spring contact finger 29 which engages the contacts 23, 24 and 25 in succession to light the bulbs 13.

Each radial row of contacts is joined by a bus bar 30 which is, in turn, electrically connected to one of the bulbs. The spring contact fingers are so arranged that they will maintain contact over a considerable period of time, while the contact arm to which it is attached, is slowly rotating. When the contact finger slides off of

contact, it will then swing over and engage the next adjacent contact.

Having described our invention, we claim:

1. An advertising sign comprising a housing, a plurality of compartments in the housing, a transparent cover on each compartment, said cover having advertisements thereon, a bulb in each of the compartments, a plurality of rows of contacts, each row of contacts being electrically connected to said bulbs, a contact finger for each row of contacts, and means to rotate said contact fingers at different rates of speed relative to each other, each contact finger continuously closing a circuit to a bulb while engaging a contact.
2. An advertising sign comprising a housing, a plurality of compartments in the housing, a transparent cover on each compartment, said cover having advertisements thereon, a bulb in each of the compartments, a plurality of rows of contacts, each row of contacts being electrically connected to said bulbs, a contact finger for each row of contacts, means to rotate said contact fingers at different rates of speed relative to each other, a plurality of pointers extending over the housing, said pointers being rotated at the same rates of speed as the contact fingers, each contact finger continuously closing a circuit to a bulb while engaging a contact.
3. An advertising sign comprising a housing, a plurality of radial walls in the housing, forming compartments, a transparent cover on each compartment, said cover having advertisements thereon, a chronometer at the center of the housing, a plurality of rows of contact buttons, a plurality of shafts, said shafts being rotated at different rates of speed, means operably connecting the shafts and the chronometer, a contact finger secured to each of the shafts, said contact finger being adapted and arranged to engage a row of contacts, and an electric bulb in each of the compartments, said bulbs being elec-

trically connected to each of the rows of contacts, each contact finger continuously closing a circuit to a bulb while engaging a contact.

4. An electric sign comprising a housing, said housing having a plurality of compartments therein, a transparent cover on each compartment, said cover having advertisements thereon, a chronometer in the center of the housing, a commutator, a plurality of co-axial shafts extending thru the center of the commutator, a plurality of concentric rows of contact buttons on the commutator, a contact arm attached to each of the co-axial shafts, said contact arm being adapted and arranged to successively engage contact buttons in one of said rows, a light bulb in each of the compartments, each of said light bulbs being electrically connected to a radial row of contact buttons, each contact finger continuously closing a circuit to a bulb while engaging a contact.

5. An electric sign comprising a housing, said housing having a plurality of compartments therein, a transparent cover on each compartment, said cover having advertisements thereon, a chronometer in the center of the housing, a commutator, a plurality of co-axial shafts extending thru the center of the commutator, a plurality of concentric rows of contact buttons on the commutator, a contact arm attached to each of the co-axial shafts, said contact arm being adapted and arranged to successively engage contact buttons in one of said rows, a light bulb in each of the compartments, each of said light bulbs being electrically connected to a radial row of contact buttons, each contact finger continuously closing a circuit to a bulb while engaging a contact.
